L. D. Giiman.

Wrench.

No 125.

AI Patented July 17, 1855.

No. 125, to original Letters Patent No. 12,690.—*For Improvement.*
In Screw-Wrenches. (Plates, p. 347.)

What I claim is, adding the tube E, with the nut G, surrounding the rod c of the movable jaw, to the arrangement of the adjustable toothed plate with springs, the toothed shank, and the eccentric, with its strap attached to the toothed plate, as set forth.

Lorenzo D. Giiman.
